Attorney

UNITED STATES PATENT OFFICE

JULIUS J. ELSTER, OF HILLSBORO, NORTH DAKOTA

CAN OPENER

Application filed June 24, 1931. Serial No. 546,640.

My invention relates to special tools, more particularly to a tool for opening cans, and it consists of the combinations, constructions, and arrangements herein shown and described.

A primary purpose of my invention is to provide a can opener which by a rapid and simple operation will enable an operator to cut the entire top from a can, thus allowing removal of the contents thereof without interference from portions of the top of the can, which is the case when the cut is made in said top.

A further object of my invention is to provide a device of the type described which has few parts, does not get out of order easily, and is simple to manufacture.

Other objects and advantages will appear as the specification proceeds, and the invention will be more particularly defined in the appended claims.

My device is illustrated in the accompanying drawing forming a part of this application, in which

Figure 1 is an elevational view of my device with parts thereof shown in section for clearness of illustration.

Figure 2 is an elevational view of the device as seen from the left of Figure 1,

Figure 3 is a fragmentary detail view of a portion of the device,

Figure 4 is an elevational detail view of a modified portion of the device, and

Figure 5 is a sectional view on line 5—5 of Figure 4.

In carrying out my invention I make use of a pair of similarly formed but oppositely disposed levers, 1, having handle portions, 2, intermediate portions 3, and jaw portions 4. The inner edges of these jaw portions may be provided with teeth 5 for allowing an auxiliary use of my device as a pair of pliers. The intermediate portions 3 are provided with aligned bores 6 and oppositely disposed and similarly formed studs 7 for purposes that will soon be made clear.

Positioned between the levers at their intermediate portions is a plate member, 8, having therein a centrally located elongated slot, 9, aligned with the bores in said levers and

a pair of slots, 10, on either side of said slot, 9, for engagement about the stud members, 7. A portion of the top edge of this plate extends upwardly to form a U-shaped arm, 11, positioned at an angle to said plate, as most clearly seen from an examination of Figure 1. This U-shaped member has in the walls thereof aligned bores in which a pin, 13, is journaled for rotation. Mounted on this pin, 13, is a rotatable cutting blade, 14, and a guide roller, 15, adjacent thereto.

For aiding in guiding the implement during the operation the plate, 8, has a lip, 16, curled downwardly from the upper edge.

A hook, 17, projecting from the sides of the member 8 permits an auxiliary usage of my device as a bottle opener for crown capped bottles, as will be later described.

On the stud shaft 18, rotatable in the aligned bores 6 of the levers and through the slot 9 of the piece 8, is mounted a toothed wheel, 19, for rotation with said stud. This stud shaft carries at its outer end a winged head, 20, having the finger holds 21 and the shoulder 22 for abutting engagement with the portion of the lever adjacent thereto.

In Figures 4 and 5 I show a modified form of cutting blade. In these figures the U-shaped arm 11 with its pin 12 mounts a stationary cutting blade 23, having the projecting portions 24 for engagement with the edges of the arm adjacent to that portion corresponding to the base of the U to prevent rotation of said blade. The roller 15 is used in this modification as in the other form.

For maintaining the levers in slightly spread position, which is the normal position of said levers prior to the can opening operation, a looped spring, 25, is provided. This spring, as appears most clearly from an examination of Figure 2, engages in eyelets, 26, formed in the ears, 27, on each of the jaw portions 4 of levers 1. It may be made of spring steel or any other suitable material. It is so graduated and formed that it will maintain the jaws in slightly spread position.

From the foregoing description, the use and operation of my device is easily under-

stood. When the operator wishes to open a can, he places the tool thereon in the manner most clearly shown in Figure 1, with the rotatable blade, or the stationary blade if such is used, abutting the inner wall of the bead 28 at the top of the can, and the notched or toothed wheel 19 adjacent to the outer wall of said bead. He then squeezes the handles 2 so that the same are forced towards one another, thus bringing the jaws 4 into close relationship against the pressure exerted by spring 25. This operation serves to swing the studs 7 about the stud shaft 18 in bores 6, which movement by the engagement of said studs 7 with slots 10 carries the plate 8 downwardly relative to the stud shaft 18 and consequently the wheel 19. The cutting blade, being positioned on this plate 8, is carried downwardly thereby into forcible engagement with the top wall of the can and opposed to the wheel 19. The operator has then only to rotate the winged head 20 with his other hand to carry the device around the top of the can by means of the frictional engagement of the toothed wheel with the edge of the can during this movement. The blade during this operation will cut through the top wall of the can at the outer edge thereof, thus neatly severing the top therefrom. During the operation the blade will be guided in proper position and the operation facilitated by the roller 15 resting on top of the bead and the ear 16 resting on top of the can. The operator has then only to release his grip and the instrument is ready for repetition of the operation.

When the operator desires to utilize the device as an opener for bottles with crown caps, he merely places the outer edge of the jaw on the top of the cap, engages the hook member 17 beneath the edge of said cap, and raises upwardly.

When he desires to utilize the device as a pair of pliers, he simply removes the spring 25 from the jaws 4 by bending the ends thereof when the spring has been secured in the eyelets by this means, or by other methods when the same has been otherwise secured.

It is thus seen that I have provided a tool for opening cans that easily and efficiently cuts the top walls from said cans to entirely remove the top thereof, thus facilitating greatly removal of the contents of the can.

It is further seen that I have provided a device of the type described which is also adapted to the auxiliary usages of opening crown capped bottles and of grasping materials in a manner similar to a pair of pliers.

What I desire to claim and secure by Letters Patent is:

1. In a can opener a pair of similarly formed and oppositely disposed levers having intermediate portions normal thereto, a swivel connection between said levers at said intermediate portions, a stud on each of said

levers but oppositely disposed relative to said swivel connection, a plate having a slot for slidable engagement with said swivel connection, and laterally extending slots on either side of said first-named slot for slidable engagement with said studs, a cutting member positioned on said plate for engagement with the top wall of a can, and a member rotatable with the swivel connection between said levers, and normally positioned in spaced relation to said cutting member, whereby movement of the handles of said levers towards one another forces said cutting member towards said second-named member for severing the wall of the can during rotation of said second-named member. 70 75 80

2. In a can opener a rotatable member for engagement with the outer wall of the bead of a can, a blade support comprising an inverted U-shaped member having a spindle 85 extending through the arms thereof, a blade mounted on said spindle for engagement with the top wall of the can, shoulders projecting from said blade for engagement with the edges of the U-shaped member adjacent to the portion corresponding to the base of the U, and means for forcing said blade support towards said rotatable member for severing the wall of said can upon rotation of said rotatable member. 90 95

3. In a can opener a pair of similarly formed but oppositely disposed levers having intermediate portions extending transversely to the axes thereof, a stud shaft swivelly mounting said levers at said intermediate portions, a stud extending inwardly at each of said intermediate portions on each of said levers the stud of one of said intermediate portions being positioned on one side of said stud shaft and the stud of the other of said intermediate portions being positioned on the other side of said stud shaft, a plate having a slot extending in the direction of the axes of said levers for engagement about said stud shaft, and a pair of laterally 100 105 110

extending slots on either side of said first-named slot for engagement with said studs, a cutting member positioned on said plate for engagement with the top wall of a can, and a member positioned on said stud shaft for rotation therewith, whereby movement of said levers towards one another during the rotation of said rotatable member forces said cutting member towards said rotatable member for severing the wall of the can. 115 120

4. In a can opener a pair of similarly formed and oppositely disposed levers, a stud shaft for swivelly mounting said levers, a stud on each of said levers the stud on one of said levers being on one side of the stud shaft and the stud on the other of said levers being on the other side of said stud shaft, a plate positioned between said levers and having a slot extending in the direction of the axes of said levers for engagement about said 125 130

- stud shaft, and laterally extending slots for engagement about said studs, a cutting member positioned on said plate for engagement with the top wall of a can, a member rotatable with said stud shaft for engagement with the outer wall of the bead of the can, and a resilient member interconnecting the ends of said levers to normally maintain said levers in partially opened position whereby movement of said levers towards one another forces said cutting member towards said second-named member to sever the wall of the can during rotation of said second-named member.
- 15 5. In a can opener a pair of swivelly interconnected levers, a stud on each of said levers, a member having slots for slidable engagement with said studs, a cutting member positioned on said slotted member for engagement with the wall of a can, and a rotatable member positioned in spaced relation to said cutting member, where by movement of the levers relative to one another forces said cutting member towards said rotatable member for severing the wall of the can upon rotation of said rotatable member.
